UNITED STATES PATENT OFFICE.

GEORGE F. GMINDER, OF NEW YORK, N. Y.

DESIGN FOR TRIMMING.

SPECIFICATION forming part of Design No. 14,666, dated February 12, 1884.

Application filed December 29, 1883. Term of patent 3½ years.

To all whom it may concern:

Be it known that I, GEO. F. GMINDER, of New York, in the county of New York and State of New York, have invented a certain 5 new and useful Design for Trimmings; and I do hereby declare that the following is a full, clear, and exact description thereof, reference being had to the accompanying drawing, and to the letters of reference marked thereon, 10 which form part of this specification, in which the single figure represents a front view of my newly-designed fringe or trimming.

A designates the heading of the fringe, which is provided with pendants B and C. These 15 pendants are arranged symmetrically, as shown, one of the pendants B, alternating with every pair of the pendants C. The pendants C are of the construction known as "figured chenille," and the figures may be of either 20 diamond, ball, or any other suitable shape. In the drawing hereto annexed I have shown the ball-shaped figures, which make an effective pattern. The intermediate pendants, B,

are constructed with laterally-projecting chenille figures D, which may be of ball, diamond, or other suitable shape. I prefer to make them of a shape corresponding to that of the figures upon the pendants C; hence they have in the drawing been shown as ball-shaped. These laterally-projecting figures will naturally depend and form an attractive pattern when combined with the pendants C, which they partly cover.

I claim—

The design for chenille fringe, which consists 35 of figured pendants arranged in pairs, alternating with single pendants having laterally-projecting figures or ornaments, as set forth.

In testimony that I claim the foregoing as my own I affix my signature in presence of 40 two witnesses.

GEO. F. GMINDER.
